DESIGN FOR A HOBBYHORSE

George W. Walker, Pleasant Ridge, Mich., assignor to B & V New Products Company, Rochester, N. Y., a firm composed of Basil G. Baldwin and Carl Voehringer

Application July 11, 1946, Serial No. 131,504

Term of patent 7 years

(Cl. D34—15)

To all whom it may concern:

Be it known that I, George W. Walker, a citizen of the United States, residing at Pleasant Ridge, in the county of Oakland and State of Michigan, have invented a new, original, and ornamental Design for a Hobbyhorse, of which the following is a specification, reference being had to the accompanying drawing, forming part thereof.

In said drawing, Fig. 1 is a perspective view of a hobbyhorse, showing my design; and Fig. 2 is a top plan view thereof. The dominant features of the design reside in those portions thereof shown in full lines.

I claim:

The ornamental design for a hobbyhorse, substantially as shown and described.

GEORGE W. WALKER.
